UNITED STATES PATENT OFFICE.

ALEXANDER JOHN ARBUCKLE, OF JOHANNESBURG, TRANSVAAL.

SETTLING-TANK.

1,020,013.

Specification of Letters Patent. Patented Mar. 12, 1912.

Application filed November 13, 1909. Serial No. 527,929.

To all whom it may concern:

Be it known that I, ALEXANDER JOHN ARBUCKLE, a subject of the King of Great Britain, and resident of Johannesburg, Transvaal, have invented certain new and useful Improvements in Settling-Tanks, of which the following is a specification.

This invention relates to vats, tanks or vessels employed for separating crushed or pulverized ore from water, cyanid solution or other liquid. Although the invention has been primarily designed for this purpose, it may also be utilized for separating the solid and liquid components of other fluid masses, particularly when the solids are in a fine state of subdivision or the particles thereof are minute, and the mass contains a small percentage of such solid matter.

The object of the invention is to provide the vessel with a very large depositing or settling area upon which the particles of solid matter can subside or settle. The parts providing the depositing or settling areas or surfaces are arranged at such an angle or inclination that the solid particles which accumulate thereupon, ultimately gravitate or fall off said areas or surfaces to the bottom or lower portion of the vessel, whence they are removed, either continuously or intermittently, by any suitable means. To insure that the accumulated solid particles shall slide off the surfaces I find that it is requisite that said surfaces be inclined at an angle of 60° (sixty degrees) or thereabout to the horizontal. It is known that once the particles of ore slimes are collected and settled, said particles cohere sufficiently to fall in a mass or body through liquid with little dispersion or diffusion. For the purpose of my invention the vessel may be in the form of an inverted truncated hollow cone or pyramid, or be of circular, square or any suitable polygonal horizontal section in its upper portion, and of inverted conical or pyramidal shape in its lower portion. The vessel is preferably provided at the top with an ordinary rim or overflow launder for receiving the separated clear liquid. The ore pulp or fluid mass may be introduced into the vessel either at or in proximity to the top or bottom thereof or at other suitable intermediate point or points as preferred. The shape and arrangement of the parts providing the settling surface or surfaces

will to some extent depend upon the internal configuration of the vessel. In the case of an inverted conical vessel then said parts may conveniently be constructed in the form of a smaller inverted truncated hollow cone or cones. To provide the requisite large depositing area a plurality of the cones are preferably provided, and said cones are preferably concentrically disposed in relation to each other and at equal or unequal distances apart, inside the vessel. The settling cones are so arranged that their lower ends are above the level of the settled solids in the bottom of the vessel so as not to impede the passage of the outflowing liquid component between the cones, and above the point or points at which the pulp or mixture is introduced into the vessel, so that the settlement of the solids will, as far as is practicable, be uninfluenced by the velocity of the inflowing stream or streams.

In the accompanying drawings I illustrate several alternative forms of my invention, and I will now proceed with a detailed description thereof.

In the drawings Figure 1 illustrates a part sectional elevation of an inverted conical vat fitted with the settling cones. Fig. 2 is a plan of a portion of Fig. 1 showing the arrangement of the concentric settling cones and the mode of supporting them inside the vessel. Fig. 3 is an elevation to a reduced scale of one of the narrow wing plates 15 for supporting certain of the cones inside the vessel. Fig. 4 is an elevation, also to a reduced scale, of one of the wide wing plates 14 for supporting the cones. Fig. 5 is a sectional elevation of a conical vat illustrating a modified form of the invention. Fig. 6 is a plan of a portion of Fig. 5. Fig. 7 is a detailed view of one of the shorter slotted cones 18, and Fig. 8 is a part sectional elevation of an arrangement of vats of another shape showing a further modification of the invention.

In Figs. 1 to 4 I illustrate the invention adapted to a conical settling vessel of large dimensions. In this case the parts providing the settling areas are constructed and arranged as a series of concentric equi-distant cones. Owing to their large dimensions, the cones are built up or constructed of a number of sections or segments. 1 represents the inverted truncated conical settling vessel constructed at the bottom with an outlet 2

for the separated solids. Vat 1 is provided around the top with an annular overflow or rim launder 3. 4 represents posts for carrying vat 1. 5 is a manhole for providing access to the interior of the tank below the settling cones. 6 represents a pipe or launder for conveying the pulp or fluid mass to vessel 1, and 7 is a vertically arranged feed pipe, into the funnel-shaped upper 10 end 8 of which, pipe or launder 6 discharges. Feed pipe 7 extends to a point below the level of the lower ends of the settling cones, so that the pulp or mass is discharged inside the vessel 1 at a point below said lower ends. 15 9 is a horizontal bridge-piece arranged inside the vessel 1 and fixed to brackets or angle pieces 10 in the interior of the vessel. 11 is a distributor of conical or other shape for distributing or spreading the inflowing pulp as it leaves the lower end of the feed pipe 7, and 12 are stays for attaching the lower end of feed pipe 7 to bridge-piece 9. 13 represents the several depositing or settling cones (of which any desired number may be provided), which are shown arranged at equal distances apart and concentrically inside each other. The interior surfaces of the several settling cones 13 are formed at an angle of 60° (sixty degrees) 20 or thereabout to the horizontal. Each of the cones is constructed in a number of sections or segments, the four outer cones each comprising sixteen such segments, and the six inner cones eight such segments. For 25 carrying the several settling cones 13, and securing the same to the inside of the vessel 1, I provide eight wide wing plates 14 (see also Fig. 4), and eight intermediate narrow wing plates 15 (see also Fig. 3). The several wing plates 14, 15 at their outer ends are riveted or otherwise secured to angle or L pieces 16 riveted or otherwise fixed to the inside of the vessel 1—see Figs. 1 and 2. The eight narrow wing plates 15 serve for 30 carrying the segments of the four outer and largest cones 13, and the eight wide wing plates 14 for carrying all the cones. The several segments of the cones are constructed on the inside or along their inner edges 35 with flanges or inwardly bent portions 17, by means of which they are riveted or otherwise suitably fixed to the wing plates 14, 15. The upper ends of the several cones terminate at the same level, which level is at a 40 suitable short distance below the annular overflow launder 3. It is apparent, that as the segments of the cones connect the several wing plates 14, 15, the latter mutually support each other at their inner ends. As 45 seen in Fig. 1, as the vertical feed pipe 7 projects through the truncated open lower ends of all the settling cones 13, a vertical annular passage is formed between the outside of pipe 7 and the five inner cones, up 50 which passage the pulp can flow to the coni-

cal spaces, channels or passages formed by and between the said five inner cones. The cones 13 may be supported in any other convenient manner inside the vessel 1. If the vessel is constructed of inverted pyramidal shape, then the parts providing the settling areas or surfaces will be of corresponding inverted pyramidal configuration. In the operation of this form of the invention, the pulp is introduced into the vessel through feed pipe 7 beneath the several settling cones 13. It then flows up through the several conical spaces, channels or passages formed between the cones, and in its passage therethrough the solid particles subside or settle upon the inner surfaces of the cones, the liquid component ultimately overflowing into the annular rim launder 3. The particles of the solid component, which collect on the settling surfaces of the cones 13, eventually slide off said surfaces, and fall to the bottom of the vessel 1.

The modified form of the invention illustrated in Figs. 5 to 7, is intended more particularly for use in comparatively small settling vessels. The inverted truncated settling vessel 1 is provided, as in the last described construction, with overflow rim launder 3, and supported in like manner, by 55 posts 4, or otherwise. In this construction a plurality of inverted truncated hollow settling cones 13 are concentrically disposed relative to each other inside vessel 1. The cones 13—which are whole, or not in sections or segments as before—are shown arranged equi-distant from one another, and their truncated inner and lower extremities form a central right conical passage extending upwardly from the lower end of the outermost to the lower end of the innermost cone 13. The angle of all the cones 13 is equal (being sixty degrees or thereabout) so that a series of concentric conical spaces or passages are formed between the cones 60 from a point near the bottom of the vessel to the top thereof, similar to the last described arrangement. In the conical space formed between the outermost settling cone 13 and the inside of the vessel 1, I arrange another series of smaller, oppositely disposed or upright truncated cones 18, which are equi-distant, and concentrically disposed in relation to each other. The cones 18 are preferably formed with slots or holes 19, placed at suitable distances apart,—see also Fig. 7—so as to allow of the passage or circulation of the pulp through and between them. The slots or holes 19 in adjacent cones 18 do not coincide, so as to break up the upward current of the pulp, and insure more perfect settlement of the solid particles upon the upper surfaces of cones 18. The lower ends of the shorter cones 18, as 65 shown, project to within a short distance 1

of the internal walls of vessel 1—see Fig. 5. The cones 18 may be affixed to, and carried by, the outermost cone 13, and the whole of the cones 13 be supported inside the vessel 1 by means of wing plates, similar to the arrangement described in connection with Figs. 1 to 4, or in any other convenient manner. The pulp introduced into the vessel flows down the conical passage formed by the truncated lower ends of the several settling cones 13, and then up through the cones 18, the liquid constituent ultimately entering launder 3, and the solid constituent falling off the settling surfaces of cones 13 and 18 to the bottom of vessel 1.

In Fig. 8 I show the invention adapted to a vessel of cylindrical shape in its upper portion and inverted conical shape in its lower portion. In this figure 20 represents the cylindrical upper portion of the vessel, and 21 the inverted conical lower portion thereof. 22 represents a conveyer casing for elevating the settled solids from the bottom of the settling vessel to the top of a further settling vessel 23, and 24 the casing of a conveyer for removing it from the bottom of said latter vessel. Inside the cylindrical portion 20 of the vessel is arranged a concentric cylinder 25, of smaller diameter than cylinder 20, so as to provide between them a vertical cylindrical passage 26. Cylinder 25 is constructed at the top to provide an overflow or rim launder 27. To the lower and inner end of cylinder 25 is fixed an inverted truncated cone 28, which provides between it and the inverted conical portion 21 of the vessel, a conical passage 29 leading to a point near the bottom of the vessel. Inside the cylinder 25, an inverted truncated cone 28, is arranged a series of equi-distant concentric settling cones 30, which between them provide conical spaces or passages. With this construction, the pulp is introduced into the upper end of cylinder 20, and flows down cylindrical passage 26 and conical passage 29, to the bottom of the settling vessel. It then flows in an upward direction through and between the several settling cones 30. The liquid component ultimately enters launder 27, while the solid component, which settles on the upper surfaces of the settling cones, falls to the bottom of the vessel.

What I claim as my invention and desire to protect by Letters Patent is:—

1. In a vessel for separating pulverized ore or other comminuted solid matter from liquid, the combination with the vessel of a plurality of inverted, truncated cones arranged inside the vessel, the upper surfaces of said cones providing settling areas upon which the solid particles settle and accumulate and ultimately slide off by gravity, the truncated lower ends of the several cones forming a central, vertical passage through

all the cones, and means for supporting the cones in position inside the vessel, said means comprising a plurality of radial wing-plates fixed to the inside of the vessel, the cones being constructed in flanged sections and fixed to said radial wing-plates, as set forth.

2. In a vessel for separating pulverized ore or other comminuted solid matter from liquid, the combination with the vessel of a plurality of inverted, truncated cones arranged inside the vessel, the upper surfaces of said cones providing settling areas upon which the solid particles settle and accumulate and ultimately slide off by gravity, the truncated lower ends of the several cones forming a central, vertical passage through all the cones, means for supporting the cones inside the vessel comprising a plurality of long, radial wing-plates and a plurality of shorter intermediate wing-plates, the long wing-plates serving for carrying all the cones and the shorter wing-plates for carrying several of the outer cones, the cones being constructed in flanged segments fixed to the wing-plates, as set forth.

3. In a vessel for separating pulverized ore or other comminuted solid matter from liquid, the combination with the vessel of a plurality of inverted, truncated, equi-distant and concentric cones positioned inside the vessel, the upper surfaces of said cones constituting settling areas upon which the solid particles settle and accumulate and ultimately slide off by gravity, the truncated lower ends of the several cones forming a central, vertical passage through all the cones, a pipe located in said central, vertical passage for introducing the feed mixture below the lower ends of all the cones, means for supporting the cones in position in the vessel, comprising a plurality of radial wing-plates fixed to the inside of the vessel, the cones being constructed in flanged sections and fixed to said radial wing-plates, as set forth.

4. In a vessel for separating pulverized ore or other comminuted solid matter from liquid, the combination with the vessel of a plurality of inverted, truncated, equi-distant and concentric cones positioned inside the vessel, the upper surfaces of said cones constituting settling areas upon which the solid particles settle and accumulate and ultimately slide off by gravity, the truncated lower ends of the several cones forming a central, vertical passage through all the cones, a pipe located in said central, vertical passage for introducing the feed mixture below the lower ends of all the cones, means for supporting the cones inside the vessel, comprising a plurality of long, radial wing-plates and a plurality of shorter intermediate wing-plates, the long wing-plates serving for carrying all the cones, and the shorter wing-plates for carrying several of

the outer cones, the cones being constructed in flanged segments fixed to the wing-plates, as set forth.

5. In a vessel for separating pulverized ore or other comminuted solid matter from liquid, in combination, a vessel having an annular overflow or rim launder for the overflowing clear liquid, a plurality of inverted, truncated, equi-distant and concentric cones positioned inside said vessel below the level of the overflow launder, the upper surfaces of said cones constituting settling areas upon which the solid particles settle and accumulate and ultimately slide off by gravity, and the truncated lower ends of the inner cones forming a central, vertical passage through all the cones, a pipe located in and of smaller diameter than said central, vertical passage for introducing the feed mixture below the lower ends of all the cones, means for securing said feed pipe at its lower end comprising a horizontal member secured inside the vessel and stays connecting the lower end of the feed pipe with

said member, a distributing cone supported 25 by said horizontal member beneath the lower end of said pipe, means for introducing the feed mixture into the upper end of the feed pipe, means for supporting the settling cones in position inside the vessel, said 30 means comprising a plurality of wide radial wing-plates and a plurality of narrow, intermediate wing-plates, the several wing-plates being secured at their outer ends to the inside of the vessel, the wide wing-plates 35 serving for carrying all the cones and the narrow wing-plates for carrying several of the outer cones, all the cones being built up of flanged segments or sections fixed to the wing-plates, as set forth.

40 In testimony whereof I have signed my name to this specification in the presence of two subscribing witnesses.

ALEXANDER JOHN ARBUCKLE.
